SEWAGE LIFT STATION HOUSING

David S. Ross, Lorain, Ohio, assignor to The Amcodyne Corporation, Lorain, Ohio, a corporation of Delaware

Filed May 15, 1963, Ser. No. 74,895

Term of patent 14 years

(Cl. D13—1)

Fig. 1.

Fig. 2.

Fig. 3.

Fig. 4.

FIGURE 1 is a front elevational view of the new housing design. The rear is substantially like the front shown.

FIGURE 2 is a side elevational view looking from the left to the right of FIGURE 1.

FIGURE 3 is also a side elevational view similar to FIGURE 2, but looking from the right to the left of FIGURE 1; and

FIGURE 4 is a top plan view of the new housing design.

I claim:

The ornamental design for a sewage lift station housing, substantially as shown and described.
